FILLING DETECTOR FOR LOOMS

Frederick Gordon Cobb, Lancaster, S. C.

Application June 8, 1933, Serial No. 674,900

18 Claims. (Cl. 139—377)

This invention relates to improved means for automatically stopping a loom when the filling becomes exhausted or broken, and also for automatically replenishing the filling supply in the shuttle upon exhaustion or breakage of the filling. In some types of looms there are no means for automatically replenishing the filling supply when it becomes exhausted, but stop motions are used to detect this failure of the filling and stop the loom and an operator replenishes the filling supply or ties the broken end and again starts the loom. In other types of looms such as battery looms, magazine looms, and the like, the filling detector means, upon exhaustion of the filling supply in the shuttle, causes the filling detector to automatically operate the filling replenishing means to place a new supply of filling in the shuttle. The improved means shown in the accompanying drawings is adapted to work on both types of looms to stop the one type having no magazine or battery, while in case it is placed on the other type having a magazine or battery, the apparatus is connected to the filling replenishing means to automatically replenish the filling instead of stopping the loom as in the case of a plain loom having no battery or magazine.

In filling detectors heretofore employed, the detector finger has been of very heavy material because it had to withstand the force to operate the stop motion or the weft or filling replenishing means, and therefore, being of heavy material, had to have a grate working in conjunction therewith. Heretofore, the portion of the filling fork which was allowed to engage the snake head or weft hammer of the loom had to be of heavy construction, because it had to withstand the strength necessary to move the starting rod hook, feeler finger, starting rod arm, take-up clutch lever arm, filling motion finger, starting rod having two bearings, filling motion spring. This required considerable force to move these parts as they had to move in a fraction of a second's time. This is why the conventional filling fork had to be made of such heavy construction. Being made of heavy construction, and therefore hard to actuate by fine filling, made it necessary to have a filling rack or grate, through which the prongs of the filling fork would pass in the absence of filling. These racks or grates accumulate lint, causing the filling fork to be actuated and thus fail to engage the weft hammer or snake head, even though the filling was exhausted from the bobbin in the shuttle and, therefore, the weaving operation would continue with no filling in the shuttle, resulting in thin places in the fabric being

woven. In my invention, employing no filling rack or grate, this imperfection is entirely eliminated.

In my invention, I use a very delicate filling feeling finger which controls other parts which engage the weft hammer or snake head, and therefore, the filling feeler finger not having to withstand the force exerted by the snake head or weft hammer, can be of very light structure and therefore requires no grate or filling fork to cause the same to be operated by the filling. It is thus seen that I not only dispense with a filling grate but also the cumbersome filling fork and use instead thereof a sensitive and delicate filling feeler finger.

It is, therefore, an object of my invention to provide a weft or filling detector for looms which will merely place into operation mechanism for moving the stop motion of a plain loom, or the weft replenishing means for a battery loom, magazine loom and the like and which is equipped with a light weight filling feeler finger which does not have to be strong enough to withstand the force necessary to move the parts heretofore listed.

Some of the objects having been stated, the invention will be more fully understood when taken in connection with the accompanying drawings, in which—

Figure 1 is a plan view of filling feeler finger and the filling slide and also a part of the operating lever for same;

Figure 2 is a side view taken along line 2—2 in Figure 1 which shows in section the lay of the loom, also a part of frame of same, as well as the guide for holding the filling slide;

Figure 3 is an enlarged view of my mechanism taken along the line 3—3 in Figure 1;

Figure 4 is an enlarged view of the left hand portion of Figure 3 which shows the knife edge pivot mounting for the filling feeler finger and showing the angular opening which limits the amount of movement of the feeler finger;

Figure 5 is an isometric view showing how the thin metal mounting or pivot is shaped when assembled with the feeler finger and the filling slide;

Figure 6 is an isometric view of filling feeler finger;

Figure 7 is an isometric view of the weighted lever, together with its pivoting pin;

Figure 8 shows the hooked lever for engaging the cross piece on the filling slide and thereby causing it to pull said slide backwardly at the proper time;

Figure 9 is an isometric view of the lay of the

loom near the shuttle box and shows the opening for the filling feeler finger to operate;

Figure 10 is a view similar to Figure 1 showing a modified form of the invention;

5 Figure 11 is a sectional view taken along the line 11—11 in Figure 10;

Figure 12 is a sectional view taken along the same line as Figure 11 but showing the parts in a different position;

10 Figure 13 is a view similar to Figure 2 and taken along line 13—13 in Figure 10 but showing the modified form of the invention;

Figure 14 is a perspective view of the filling feeler finger and support therefor as shown in 15 Figures 11 and 12;

Figure 15 is a perspective view of the upper dog adapted to be engaged by the feeler finger;

20 Figure 16 is a perspective view of the lower dog adapted to be released by the feeler finger 25 engaging the upper dog shown in Figure 15.

25 Referring more specifically to the drawings, the numeral 10 indicates a portion of a loom frame having mounted thereon conventional slide guide 11 having sidewalls 12 and 13 in which is slidably mounted filling slide 14 having a hook 15 on one end thereof connected with bobbin renewal lever 16 which is in turn connected to the replenishing mechanism (not shown) such as a battery head and the like as the mechanism is 30 adapted to cooperate within any automatic weft replenishing loom.

35 The filling slide projects toward lay 17 of the loom having reeds 18 therein and reed cap 19 and a shuttle box 20 for reception of a shuttle 21 at each end of the lay, said lay being reciprocated in a conventional manner by being mounted on arms 22. Shuttle 21 supports a bobbin 24 from whence thread 25 is drawn as the shuttle is thrown back and forth from one end of the lay of the 40 loom to the other thru the warp 25a.

45 Filling slide 11 has a slot 26 therein in which filling motion lever 27 reciprocates together with its associated parts on the upper end thereof. On the upper end of filling motion lever 27 is pivoted at 28 a member 29 which normally slides back and forth with filling motion lever 27 by having slot 30 receiving cross piece 31 on filling slide. The cross piece 31 on filling slide is joined to the side portions 32 and 33 of filling slide. A 50 clamp member 34 has the clamping portions 35 and 36 adapted to engage portion 33 of filling slide and projects thru holes in the ends of portions 33 and 32. Portion 37 clamps against the outer surface of portion 32 after penetrating the 55 hole therein. Pivoted on portion 38 of clamp 34 is my filling feeler finger 40 having a slot 41 therein closed at one end by portion 42 integral therewith. Filling feeler finger 40 has approximately triangular perforations 43 and 44 60 therein which are penetrated by portion 33 of clamp 34. Filling feeler finger 40 projects downwardly and has roughened or serrated portion 45 adapted to engage the filling 25, and prevent slipping of the same when the lay of the loom 65 swings toward the portion 45 to move the thread 25 to point 18b near temple 18c. Member 29 has longitudinally disposed slot 46 therein and a hole 47 communicates with slot 46 and slot 30. The 70 serrated portion 45 prevents filling thread 25 from slipping on the feeler finger.

A drop hook lever 48 is pivoted on pin 49 and has hook 50 on one end thereof adapted to penetrate perforation 47 to engage cross piece 31 when released by raising of a weighted lever 52 pivoted 75 on member 29 as at 53 and having a weight por-

tion 54 to normally press member 52 against drop hook lever 48. A transverse portion 55 is disposed between the sidewalls of the upper portion of the member 29 for joining the two sidewalls together. Member 52 has a shoulder 56 adapted to be engaged by portion 42 of filling feeler finger when not moved to raised position by the presence of a filling thread 25.

5 In normal operation when member 29, reciprocating back and forth beneath portion 42 of filling feeler finger, reaches point 42, if a filling thread 25 is present this will hold portion 42 out of engagement with shoulder 56 and shoulder 56 will slide beneath portion 42 and filling slide 14 will not be operated. In case a filling thread 25 15 is absent then portion 42 of filling feeler finger will engage shoulder 56 and lift lever 52 and allow drop hook lever 48 to have its hook 50 engage cross piece 31 and this will move filling slide 14 20 and operate the welt replenishing apparatus in 25 any conventional automatic loom.

While the filling feeler finger is shown as roughened or serrated, it is evident that it can be made without serrations, may be flat or square in cross-section, can be covered with fibers, and 25 may be made of steel, iron, wood, fiber, brass, copper or any other material or shape necessary to conform to conditions under which it operates.

30 The pivotal mounting of the filling feeler finger is such that a knife-edge mounting is practically 30 acquired and the triangular perforations 43 and 44 limit the amount of rotation which filling feeler finger 40 has on portion 38. The portion 45, and in fact the entire filling feeler finger, is 35 very light and, therefore, no grate is required and it is very sensitive in its operation and by elimination of a grate the action is more positive and false indications are eliminated which sometimes occur when loose threads are lodged in the conventional grate.

40 Referring particularly to Figure 3 it is to be noted that it is necessary for the filling motion lever to travel to the right until hook 50 engages cross piece 31 before any movement is imparted to filling slide 14. During this time the filling 45 slide is stationary and therefore the pivot on which the filling finger is mounted is stationary.

45 The above described motion causes the rear portion of the filling feeler finger to raise the weighted lever 52 or the hook lever 48 allowing it 50 to pass thru opening 50 and allowing it to fall into the path of the cross piece 31 on the filling slide. The filling motion lever has a much greater stroke than that between the cross piece and the hook on the lever, and this excess motion 55 then carries the filling slide forwardly or to the right in Figure 3 causing it to operate the bobbin replenishing mechanism.

50 In Figures 10 to 16 inclusive, a slightly modified 60 form of the invention is shown, especially the type of feeler finger and the mechanism controlled thereby for operating the stop motion mechanism of the loom. Similar reference characters are used in Figures 10 to 16 inclusive to indicate parts which are the same as in Figures 1 65 to 9 inclusive.

65 Conventional slide 14, having the portions 32 and 33, has therein a bolt 60 which pierces members 61 and 62 which are forked as at 63 and 64 70 for engaging ribs 65 and 66 on members 32 and 33. These members 61 and 62 are pierced by bolt 60. The members 61 and 62 are joined by a portion 67. A bolt 68 passes thru portions 61 and 62 on which is pivotally mounted a feeler finger 75

mechanism having a feeler finger 69 and coiled as at 70 loosely around bolt 68 and the other portions thereof are formed into a loop 72 which upon exhaustion of the weft is adapted to engage a mechanism hereinafter described.

Bolt 60 penetrates holes 61a and 62a in members 61 and 62 and has spacer tubes 75 and 76 therearound.

Weft hammer 27 has a member 80 pivoted on bolt 28, said member having a transverse slot 81 in which cross member 31 is adapted to have movement. This member 80 has also upstanding parallel walls 82 and 83 between which is pivoted a lower dog 84 on pin 85 mounted in portions 82 and 83. This dog has a shoulder portion 86 adapted to engage cross portion 31 when allowed to fall. Immediately above dog 84 is pivoted an upper dog or weighted lever 87 which is pivoted on pin 83 likewise mounted in side members 82 and 83. The lower portion of member 87 is made to conform to the upper edge of dog 84. The upper edge of member 87 has a hooked portion 90 therein which is adapted to be engaged by the loop 72 of the feeler finger when a filling 25 is exhausted from the shuttle in the position shown in Figure 10 or in fact when the shuttle is thrown to the other end of the lay. Member 87, as will be observed, has the right hand portion thereof in Figures 11 and 12, designated by 91, heavier than the other end, the other end being pointed as at 92.

It is seen that when a filling thread 25 is not present on a reciprocation of the lay of the loom that loop 72 will engage notch 90 and will raise the heavy end 91 of upper dog 87 upon reciprocation of weft hammer of snake head 27 and the left hand end of dog 84 being heavier than the right hand end will fall down and as the weft hammer oscillates to the right in Figures 11 and 12 this will cause the shoulder or hooked portion 86 to engage the cross member 31 and move the filling slide to operate the stop motion of the loom or operate the replenishing mechanism in case the loom is a battery loom or a magazine loom or the like.

One important feature of the mechanism shown in the Figures 10 to 16 inclusive over that shown in Figures 1 to 9 inclusive is that in case dog 84 should become stuck on account of lint, grease and the like and not fall downwardly when dog 87 is raised to the position shown in Figure 12 that upon further oscillation of weft hammer 27 to the right in Figures 11 and 12 the dog 87 would be raised to vertical position. In other words, the portion 91 would be rotated in a counter-clockwise direction and the tip 92 of the dog 87 would engage the upper surface of the left hand end of dog 84 and positively force it downwardly to cause it to engage the cross member 31 to stop the loom or replenish the shuttle with a new bobbin, depending upon the type of the loom.

In the drawings and specification, there has been set forth a preferred embodiment of the invention and although specific terms are employed, they are used in a generic and descriptive sense only and not for purposes of limitation, the scope of the invention being set forth in the appended claims.

I claim:

1. Automatic weft replenishing means for looms having a filling slide and a filling motion lever, movable means on the lever for engaging the slide, other movable means on the lever for normally holding the first movable means out of

engagement with the slide, a filling detector having means for engaging said other movable means in the absence of a filling thread for releasing said first movable means for engagement with the filling slide.

2. Automatic weft replenishing means for looms comprising a filling slide and a reciprocating filling motion lever, movable means operatively connected to the filling motion lever for engaging said slide, pivoted means for normally holding said movable means out of engagement with said slide, a single filling detector having means for engaging said pivoted means when unaffected by a filling thread for releasing said movable means for engagement with the filling slide.

3. Automatic weft replenishing means for looms comprising a filling slide having connection with filling replenishing means, a filling feeler finger movable by filling being woven, a filling motion lever reciprocable with relation to said slide and having a hooked pivoted member for engaging said slide, pivoted means for normally holding the hook out of engagement with said slide, the filling feeler finger being engageable with said pivoted means in the absence of a filling thread in the lay of the loom to raise said pivoted means to release said hooked pivoted member to allow it to engage said filling slide to operate the same.

4. Weft replenishing means for automatic looms having a filling slide and a filling motion lever, a filling detector pivotally mounted on said filling slide, means on the filling motion lever for engagement with the filling slide, other means for normally holding said means on the filling motion lever out of engagement with said slide, said other means being engageable by said filling detector when said finger is unaffected by a thread for releasing said means on the filling motion lever for engagement with the slide.

5. Detector mechanism for looms having in combination a detector slide, a filling detector finger pivotally mounted on the slide, a filling motion lever, a member pivoted on the filling motion lever and being slidably mounted with relation to the filling slide, a weighted member having a projection thereon engageable by one end of the filling detector in the absence of filling being in the loom and a hook member releasable by the raising of said weighted lever for engaging said filling slide for operation of the replenishing mechanism of the loom.

6. In a filling detector for looms, a filling motion lever, a filling slide, a bobbin replenishing mechanism connected to said filling slide, a member pivotally mounted on said filling motion lever and slidably mounted in said filling slide, a hooked member pivotally mounted in said pivoted member and being adapted to engage said filling slide when in lowered position, a weighted member pivotally mounted in said pivoted member and being adapted to normally rest on said hooked member for holding it out of engaging position with said filling slide, a filling detector normally resting on said weighted member and being raisable by engagement with the filling out of contact with said weighted member as said weighted member is reciprocated beneath said filling detector.

7. Means for automatically operating weft replenishing means for looms, comprising a filling slide and a filling detector mounted thereon, means for limiting the movement of the filling detector, movable means controlled by the filling

- detector, other movable means controlled by the first movable means for engaging the filling slide, a member slidably mounted in the filling slide in which both of said movable means are mounted and means for imparting reciprocatory movement to the slidably mounted member.
8. Means for automatically operating a weft replenishing means for looms comprising a filling slide and a reciprocating filling motion lever, movable means operatively connected to the filling motion lever and having means therein for engaging said slide, a pivoted weighted means for normally holding the means for engaging the slide out of engagement with said slide, a filling detector controlling said pivoted weighted means, said detector having means thereon for limiting its movement.
9. Means for automatically operating the weft replenishing means for looms comprising a filling slide having a weft feeler pivotally mounted thereon, a member slidably mounted in the filling slide and means driven by the loom for reciprocating the same, a plurality of levers pivotally mounted in said member, one of said levers being engageable by the weft feeler in the absence of weft, another of said levers being normally held out of engagement with the filling slide by the first lever, and being engageable with the filling slide when the first lever is engaged by the weft feeler.
10. Means for automatically operating the weft replenishing means for looms having a filling slide and a weft feeler member pivotally mounted thereon, means for limiting the movement which may be imparted to the feeler member by engagement with the weft being woven in the fabric in the loom, a member slidably mounted in the filling slide and means for reciprocating said member in said filling slide, two levers pivoted one about the other in said member, means on the upper lever for engagement with the feeler member for controlling the same, the upper lever being normally supported by the lower lever to normally hold the lower lever out of engagement with the filling slide, said lower lever having means for engaging the filling slide when the upper lever is engaged by the feeler member.
11. Mechanism for detecting an absence of weft in a loom comprising a filling feeler finger movable by the filling upon each reciprocation of the weft hammer, a filling slide and means mounted on the weft hammer for reciprocation in the filling slide, a dog mounted in the means mounted on the weft hammer for engaging the filling slide, other means for normally holding the dog out of engagement with the filling slide, a projection on the other means engageable by the filling feeler finger in the absence of weft for raising the other means and allowing the dog to engage the filling slide to operate the replenishing means, stop motion means and the like in the loom, and a second projection on the other means for positively forcing the dog into engagement with the filling slide when it fails to do so by the action of gravity.
12. In a weft detecting mechanism in a loom having a weft hammer and a filling slide, means on the weft hammer for engaging the filling slide, other means for normally holding the first means out of engagement with the filling slide, the other means being operable by the filling feeler finger in the absence of filling for releasing said first means to cause it to engage the filling slide to replenish the weft, stop the loom and like operations.
13. Weft replenishing means for a loom having a filling slide, weft hammer, and filling feeler finger for engaging the weft outside the warp, means mounted on the weft hammer for engaging the filling slide and moving the same, other means normally holding said first means out of engagement with the filling slide, means engageable by the filling feeler finger in the absence of filling in the weaving operation for releasing said first means and means on said other means for forcing said first means into engagement with the filling slide upon exhaustion of filling.
14. In a loom, means for stopping the loom, replenishing the weft therein and the like, comprising a filling slide, a weft hammer mounted for reciprocation in said filling slide, means on the weft hammer for engaging said filling slide to move the same to replenish the weft, stop the loom and the like, other means on the weft hammer for normally holding said first means out of engagement with the filling slide, a pivoted weft feeling finger mounted on the filling slide and adapted, in the absence of weft, to engage said other means to allow said first means to engage the filling slide, said other means having a portion thereof adapted to engage said first means and force it to engage said filling slide when it fails to fall by gravity after being released by said other means.
15. In a filling detector having a filling slide and a weft hammer mounted for reciprocation in the filling slide, means carried by the weft hammer for engaging and moving the filling slide, means normally holding said first means out of contact with the filling slide, a filling feeler finger having a portion adapted to engage said second means in the absence of filling to allow said first means to engage and move the filling slide.
16. Weft replenishing means and the like for looms comprising a filling slide, a single pronged filling feeler finger having an uneven surface for engagement by the filling in the loom, a weft hammer mounted for reciprocation in said slide, a pivoted hook carried by the weft hammer and normally held out of engagement with the filling slide and controlled by the filling feeler finger to engage and move the filling slide in the absence of filling in the warp.
17. Weft replenishing means, stop motion means and the like for looms comprising a filling slide, a weft hammer mounted for reciprocation in said slide, a single pronged filling feeler finger pivotally mounted on the filling slide, means carried by the weft hammer and held normally out of engagement with the filling slide and engageable by the filling feeler finger in the absence of filling, to move said means into engaging position with relation to the filling slide to move the filling slide.
18. A loom having a filling feeler finger having a series of alternating cavities and depressions in the portion thereof engageable by the filling whereby the tension on the filling will move the filling feeler finger in the absence of a grate, and means controlled by the finger for controlling the loom.

FREDERICK GORDON COBB.
